CLAIM

The ornamental design for a jewelry pendant, as shown and described.

DESCRIPTION

FIG. 1 is a front perspective view of a jewelry pendant according to my design;

FIG. 2 is a front elevational view thereof;

FIG. 3 is a back elevational view thereof;

FIG. 4 is a side elevational view thereof;

FIG. 5 is a top elevational view thereof; and,

FIG. 6 is a bottom elevational view thereof.

The broken lines illustrating a chain depict environmental structure and form no part of the claimed design. All other broken lines depict portions of the jewelry pendant that form no part of the claimed design.
